UNITED STATES PATENT OFFICE.

WILLIAM MAVER, JR., OF JERSEY CITY, NEW JERSEY, ASSIGNOR TO THE BALTIMORE AND OHIO TELEGRAPH COMPANY, OF BALTIMORE, MD.

BRANCH CIRCUIT FOR QUADRUPLEX TELEGRAPHS.

SPECIFICATION forming part of Letters Patent No. 340,137, dated April 20, 1886.

Application filed October 9, 1885. Serial No. 179,419. (No model.)

To all whom it may concern:

Be it known that I, WILLIAM MAVER, Jr., a citizen of the United States, residing in Jersey City, in the county of Hudson and State of New Jersey, have invented certain new and useful Improvements in System of Circuits for Quadruplex Telegraphs, of which the following is a specification.

In operating a quadruplex-telegraph system it sometimes occurs that it is desirable to lease one set of instruments, or, as it is termed, "one side," of the system to outside parties—for instance, to a broker. It is desirable that such party shall have full control of that side of the system and be able to operate as though it were a separate single wire. It has been customary to so organize the apparatus that the lessee may receive the messages which are being sent from the central office, and, under certain circumstances, transmit back to the central office.

The object of my invention is to provide a system wherein the lessee may receive the messages which are being transmitted to or from any of the other stations connected with the corresponding side of the quadruplex system, and also break in and transmit to all of such stations with equal facility.

In carrying out the invention the apparatus is organized substantially as follows: For convenience, it may be considered that at one station of a quadruplex system there is located apparatus for transmitting to and receiving from three different distant stations. It is desired then to include in the system the office of a broker located in the neighborhood of the home station, and to give to him the control of one side—say the polar side—of the system whenever desired. The continuity-preserving transmitter is included in the local circuit controlled by the polar relay of each set of instruments, and a conductor leads from the transmitting-point of one of these transmitters to the lever of the second, and likewise a conductor leads from the transmitting-point of the second to the lever of the third transmitter. Suitable switches are provided whereby the transmitters and these conductors may be made to constitute one continuous circuit. The circuits are further so organized that when

the transmitters are in one position the circuit will be completed from the earth through the entire system of continuity-preserving transmitters and back to earth. At some suitable point in the circuit thus made there is located a battery, and the conductor leading from one of the transmitters to a succeeding one is extended to form a loop including the lessee's office. At this office there is placed a receiving-instrument and a key. Whatever messages are transmitted upon the polar side from any of the distant points connected with the system will be sent through the loop-conductor by the corresponding transmitter, and will be recorded by the lessee's receiving-instrument. The lessee may at any time break in, however, by simply operating his key to break the connections of the loop. By making and breaking the connections of the loop-circuit the several transmitters controlling the outgoing lines from the central station may be operated, and thus the lessee is enabled to transmit to all the distant stations.

In the accompanying drawings, Figures 1 and 2 are diagrams illustrating the general organization of the apparatus.

Referring to these diagrams, L' , L^2 , and L^3 represent a series of telegraph main lines of a quadruplex system, leading from a central station to as many distant points. These lines are respectively provided with pole-changing transmitters P' , P^2 , and P^3 , adapted to transmit currents of either polarity from corresponding batteries, O' , O^2 , and O^3 . Each pole-changer is provided with a corresponding actuating-magnet, p' , p^2 , and p^3 , included in the circuits of corresponding local batteries, o' , o^2 , and o^3 . A key, k , is also included in each of these circuits, by means of which the pole-changer is operated. In each main line there is included a polar relay, as shown at R' , R^2 , and R^3 , respectively. These are rendered responsive to incoming but silent to outgoing currents in any suitable manner. The lines are further equipped with neutral relays and corresponding transmitters; but these are not here represented, as it is necessary only to show the polar side of the system.

For the purpose of operating all the pole-changers together when it is desired, a series

of transmitters, T' , T^2 , and T^3 , and three point switches, A' , A^2 , and A^3 , are employed. The latter are respectively included in the circuits of the local batteries $o' o^2 o^3$. When in the positions shown in Fig. 1 upon their respective points a' , a^2 , and a^3 , these switches close their respective local circuits through their respective electro-magnets $p' p^2 p^3$. Each switch is provided with a second point, b' , b^2 , and b^3 , respectively. The point b' is connected by a conductor, 2, with the contact-spring t of the transmitter T' . The lever of this transmitter is connected by a conductor, 3, with the point a' . A conductor, 1, connects one pole of the battery o' with the earth at G' . A conductor, 7, leads from the contact-point s' of the transmitter T' to the pole of the battery o^2 , corresponding to that of the battery o' , which is connected with the earth. A corresponding system of circuit-connections is made with respect to the transmitters T^2 and T^3 , the contact-point of the last transmitter being connected with the earth at G^3 . The transmitters T' , T^2 , and T^3 are designed to be made to respond to incoming currents by the operations of the corresponding polar relays, R' , R^2 , and R^3 , which serve to make and break the connections of corresponding local batteries, o^4 , o^5 , and o^6 , through corresponding magnets, q . The connections are such that when no messages are being sent in upon the lines L' , L^2 , and L^3 , the transmitters T' , T^2 , and T^3 will remain at rest in the positions shown in the drawings, completing the circuit-connections from the earth at G' to the earth at G^2 , provided only the several switches A' , A^2 , and A^3 are upon their respective contact-points b' , b^2 , and b^3 , as shown in Fig. 2.

It is designed that the conductor l , connecting one of the transmitter-points with the local circuit of the succeeding pole-changer, shall be extended to the branch or lessee's office, which is to be included in the system, as represented. There is provided at such office a key, C, and a sounder or other receiving-instrument, D. A battery, O, is also included in this conductor, or at some point in the circuit, and the entire system of batteries are connected in series. When the circuit is closed, the several magnets p' , p^2 , and p^3 , and that of the sounder D, are all vitalized. By interrupting the circuit at any point they will all become demagnetized. By operating any one of the keys k' , k^2 , or k^3 it is apparent that all the pole-changers will be actuated and the message transmitted automatically upon the several lines L' , L^2 , and L^3 , and also through the instrument D at the branch or substation. The operator at this station may, by means of his key, break in and transmit in precisely the same manner as though upon a single Morse circuit. Considering now that a message is being received from the line L' , this will operate the transmitter T' , and thereby cause the circuit-connections to be interrupted and established through the magnets above referred to. Messages from either of the other lines, L^2

and L^3 , will produce a similar effect, so that incoming messages from any line will be transmitted through the station upon the other two lines, and will also operate the receiving-instrument D. This instrument may be constructed as a sounder or a relay, or in any other suitable manner to serve the purposes of a receiving-instrument, and it is evident that it, together with the key C, constitutes a complete station apparatus for receiving and for transmitting in both directions. It should be here noticed that when messages are being received from any line— L' , for instance—the pole-changer corresponding thereto will not be actuated, for the reason that when the transmitter T' is in the position shown in the drawings the circuit of the several batteries is complete through the magnet p' , and when the transmitter is in the reverse position the circuit of the battery o' is complete through the conductor 2, spring t , lever s , and conductor 3, and therefore the magnet will remain vitalized by reason of the current from this local battery.

I claim as my invention—

1. The combination, substantially as herein-before set forth, with a series of quadruplex-telegraph main lines and the set of instruments pertaining to one side of the same, of a loop-conductor connecting two or more of said sets of instruments, which conductor extends through a branch office and transmitting and receiving apparatus included therein. 100

2. The combination, substantially as herein-before set forth, of a series of quadruplex-telegraph main lines converging to a single station, a branch office, a loop-conductor extending from said station to include said office, and means for transmitting upon all of said lines and through said loop-conductor simultaneously. 105

3. The combination, substantially as herein-before set forth, of a series of main lines, transmitting and receiving devices applied to each of the same, means for transmitting upon all of said lines simultaneously, a branch office or station, telegraphic instruments located at said office, a circuit including said instruments, and means for controlling the connections of said circuit operated by any of the said transmitting or receiving devices, substantially as described. 110

4. The combination, substantially as herein-before set forth, in a quadruplex system, of means for transmitting upon radiating lines of said system either independently or together, a branch station, and a conductor extending from one of said line-transmitters through said station to a second of said line-transmitters, substantially as described. 120

5. The combination, substantially as herein-before set forth, of two or more transmitters, electro-magnets, and local circuits for operating the same, two or more receiving-instruments, local circuits having their connections controlled thereby, transmitting devices operated by currents in the last-named local cir- 130

cuits, means for connecting one of the first-named local circuits through one of said transmitting devices with a second of the first-named local circuits, a battery included in the circuit thus formed, and a telegraph receiving and transmitting instrument also included therein.

6. The combination, substantially as herein-before set forth, of the lines L' and L^2 , the transmitters T' and T^2 , the batteries o' , o^2 , and O , the loop-conductor l , the instruments included therein, means for operating said transmitters, and the circuit-connections, substantially as described.

15 7. The combination, substantially as herein-

before set forth, of a series of quadruplex-telegraph main lines converging to a single station, a loop conductor connecting the various quadruplex sets in said single station, and means for transmitting upon all of said lines 20 and through said loop-conductor simultaneously.

In testimony whereof I have hereunto subscribed my name this 8th day of October, A. D. 1885.
